HYGROSTAT

Budolph Miller, Detroit, Mich., assignor, by mesne assignments, to Edward C. Lamlein, Detroit, Mich.

Application October 30, 1930. Serial No. 492,185

4 Claims. (Cl. 297—1)

- This invention concerns automatic controls, and relates more particularly to hygrostats, or mechanisms adapted to be responsive to variations in the moisture content of the surrounding atmosphere, and which include an electrical switch arranged to be automatically thrown, to close or open an electric circuit when the humidity of the air falls below or rises above certain desired levels.
- 10 An important object of this invention is the provision of such a hygrostatic controlling device which will be extremely simple and compact, but which nevertheless will produce mechanical action in response to the required humidity changes which is of sufficient extent and force to directly actuate a controlling switch carrying a relatively heavy current, as for a suitable humidifying device, eliminating the necessity of an interposed relay.
- 15 Another object of this invention is the provision of such a device which will be of unprecedented sensitivity and quickness in responding to humidity variations.

A further object of this invention is the provision of a novel and highly efficient controlling element for such a device which is productive of greater and more positive mechanical movement for its size than any heretofore developed, and which is of such form as to render its entire surface effective.

Other objects and advantages will be apparent from the following description, wherein reference is made to the accompanying drawings illustrating a preferred embodiment of my invention and wherein similar reference numerals designate similar parts throughout the several views.

In the drawings:

Figure 1 is a perspective view of my improved hygrostat with the cover in place, assembled and ready for operation, as it appears when mounted upon a wall or wherever desired, bringing out its symmetrical and pleasing appearance.

45 Figure 2 is a front elevational view of the hygrostat with the cover removed.

Figure 3 is a front elevational view of my device with both the cover and the controlling element removed.

50 Figure 4 is a vertical sectional view taken substantially on the line 4—4 of Figure 3.

Figure 5 is a sectional view taken substantially on the line 5—5 of Figure 4.

55 Figure 6 is a sectional view taken substantially on the line 6—6 of Figure 4.

Figure 7 is a sectional view taken substantially on the line 7—7 of Figure 4.

Referring now to the drawings:

Reference character 10 indicates a supporting back plate for my device, which may conveniently be cast from a suitable metal, as aluminum or an alloy thereof, and integrally with which certain of the supporting members may well be cast. The supporting members for the controlling element comprise the upstanding rigid posts 11, 12, 13, 14 which extend forwardly from the back plate, and carry tapped apertures at their ends, into which the machine screws 15, 16, 17, and 18 may be screwed.

The controlling element comprises a thin baseless wooden cone or conical disk 20 (Figures 2, 4, and 5) the outer edge of which is tightly secured by a restricting metallic band 21, which prevents it from expanding outwardly. The cone may be formed of any desired angularity, depending upon the extent of movement which it is desired to have its apex produce, and other mechanical considerations. It is preferably cut with the grain of the wood coaxial with the finished cone, in order that the end of the grain may be exposed upon its two surfaces. As shown, the cone is preferably formed with a relatively thin wall, so that it is in reality little more than a conic surface. More strictly speaking, the controlling element of the preferred form herein disclosed is a frusto-conical surface, since it does not itself come quite to a point, but is truncated to receive the bushing 19. The formation of the ring 21, which constricts the cone when moisture tends to expand it, is clearly shown in Figure 4, preferably being grooved and tightly fitted about the edge of the cone, as there shown. It will be obvious that since the cone cannot expand outwardly at its base, moisture-induced expansion of the cone forces its apex outwardly along the line of its axis, increasing the altitude of the cone. Conversely, as the cone dries out, its apex moves inwardly and the cone tends to flatten. It is this movement of the apex of the cone which is utilized to operate my device.

The controlling cone is mounted upon the four posts 11, 12, 13, and 14 by clamping the restricting ring 21 beneath the heads of the machine screws 15, 16, 17, and 18. The ends of the posts may be suitably cut away or notched to receive the ring, as at 22, 23, 24, and 25, the ring fitting accurately within the four ledges thus formed.

Enough of the center or apex of the cone is cut away to enable fitting the bushing 19 therein, 110 which bushing is internally threaded to receive

the adjusting screw 26, by means of which movement of the point of the cone is transmitted to a lever, as 27, against which its end bears, (Figure 4). The lever as herein shown, is pivoted 5 adjacent one extremity upon a horizontal axis, as by mounting it within the yoke 28, rigidly supported from the back plate 10, between suitable bearings, as 29—30. The bearing 30 may be adjustable, as shown in Figure 3. The long arm 10 of the lever 27 projects upwardly, and carries a cam surface 32 at its top which engages a roller 31 carried by the short arm of a bellcrank 34, also mounted to pivot about a horizontal axis, which, however, is perpendicular to the axis of 15 the lever 27. In this embodiment of my invention, the cam surface is formed to force the roller, and consequently the short arm of the bellcrank, upwardly when the lever arm 27 moves toward the back plate, and to permit its descent when the 20 lever arm 27 moves forwardly and away from the back plate. The short arm of the bellcrank, which is designated 34, projects outwardly almost horizontally, the longer arm 35 depends almost vertically. The supporting pivot pins 25 which provide the bearings for the bellcrank may be carried by and engage with the support 36, which is also rigidly secured to the back plate. The bellcrank pivot pins are designated 37 and 38, the latter of the two being adjustable. It 30 will be seen that cone bearings are used for both the bellcrank and the lever 27, and that the fixed pins (29—37) are carried by their respective levers, while the adjustable pins (30—38) are carried by their respective supports, although 35 this construction is of course optional. Integral with the long lever arms 27 is a shorter arm 57, projecting substantially horizontally toward the back plate. A tensile spring 58 connects the lever arm 57 and the short arm of the bellcrank, 40 thereby constantly urging the long arm 27 forwardly away from the back plate, and simultaneously urging the short arm of the bellcrank downwardly upon the cam surface 32.

The movement directly induced by the cam 32 45 which is part of the lever 27 is multiplied by the bellcrank, the long arm of which is used to tilt the mercury switch 40 which controls the circuit which the device is desired to govern. The preferred shape of the long arm 35 of the bellcrank 50 is best shown in Figure 3.

The mercury switch is of conventional construction, comprising a sealed glass tube, preferably containing an inert gas, a quantity of mercury, and a pair of spaced contacts adapted to 55 be electrically connected by the mercury when the tube is tilted in one direction, and to be disconnected when it is tilted in another direction. The contacts are connected to terminals 41—42, which are sealed in the glass in the tube, extending 60 therethrough. Insulated flexible connectors 45—46 are fastened to the terminals outside the tube, and run to binding posts or other suitable terminals for the device itself, 43—44.

To allow its being tilted about a horizontal 65 axis in the manner necessary to throw it, the mercury switch is preferably suspended from the pivot pin 47, which is pointed at its ends and journaled in the back plate and in a depending bearing arm 48 rigidly carried by the yoke member 28, at its end, as is best shown in Figure 4. An adjustable bearing 54 may be provided for the pin 47, carried by the arm 48. A depending 70 arm 49 affixed to the pivot pin 47 supports the tube and its retaining member, which latter is 75 formed of a sheet metal strip 51, wrapped about

the tube and secured to the arm, as by the screw 52. Actuation of the supporting arm 49, and consequent tilting of the tube, is through the agency of the pin 50, or other suitable projection carried by the arm, with which the bifurcated end 53 of the long arm 35 of the bellcrank engages. To prevent their interference with the free rotatability of the switch, the "pigtail" connectors 45—46 may be wrapped loosely one or two revolutions about the pivot pin 47, as shown in Figures 3 and 4.

It will now be apparent that if the controlling cone shrinks, as by drying out, so that its apex moves inwardly, in a direction away from the back plate, sufficiently, the forward movement of the lever 27 and consequent downward movement of the short arm 34 of the bellcrank, both spring-induced, will swing the long arm 35 of the bellcrank to the left, tilting the switch to the right or "on" position. When this occurs, if a humidifying device and a source of current (not shown) are properly connected to the switch, the humidifier will be turned on, and will remain on until the reverse operation takes place. This occurs when the cone swells sufficiently, due to the absorption of the proper amount of moisture, to force the end of the adjusting screw outwardly sufficiently to move the lever arm 27 back toward its initial position and throw the switch in the opposite direction, which will of course turn off 105 the humidifier or humidifiers, any desired number of which may be controlled by a single control unit. To controllingly vary the point at which the tripping of the switch takes place, it is of course merely necessary to adjust the regulating screw 26.

I also may provide visible indication of the percentage of humidity contained in the air by provision of the indicating needle 60 and its actuating mechanism, for cooperation with which the outside of the casing may be fitted with a suitable scale, as 61, Figure 1. The needle is formed as a continuation of the lever 63, to the end of which it is affixed. The lever 63 may be

swung about a horizontal axis, which is furnished by the rod 64, to which the lever is rigidly attached. The rod 64 is journaled in substantially perpendicular relation to the back plate, between the back plate, which provides one bearing, and a bracket 66 which provides the other, and which is supported by being affixed to the yoke member 28, as by the machine screw 67. Secured to the rod 64 is the short lever 68, which is bifurcated at its end, the slot thus formed being of a size and positioned to receive the end of the lever 115 arm 57, which is a portion of the lever 27. The short bifurcated lever 68 may be secured to the shaft 64 in any suitable manner, as by being affixed to or integral with the sleeve 65, which may be forced on the spindle to engage the same by friction. When the long lever arm moves about the axis 29—30, the short lever arm 57 is simultaneously moved up or down, and its end being in engagement with the slot in the lever 68, it rotates the shaft 64, and so moves the needle 60 over the scale. The slot in the lever 68 is designated 69, and the construction of this part is shown in detail in Figure 7, the entire needle-operating mechanism is brought out best in Figures 4, 5, and 6.

A suitable cover 70, for the device may be formed with open or grilles or screened sides, as shown in Figure 1, to allow free circulation of air around and against the controlling cone, and a suitable aperture, as 71, may be formed to

permit insertion of a screw driver to enable turning the regulating screw 26 without removing the cover. A suitable slot 76 is also provided in the casing through which the needle may pass 5 and to allow its movement over the scale.

While it will be apparent that the illustrated embodiment of my invention disclosed is well calculated to adequately fulfill the objects and advantages primarily stated, it is to be understood 10 that the invention is susceptible to variation, modification and change within the spirit and scope of the subjoined claims.

I claim:

1. A controlling element for humidity-responsive apparatus comprising a stiff dished member 15 expansible and contractible under varying humidity conditions, and means for restricting outward expansion thereof.

2. A controlling element for humidity-responsive apparatus comprising a thin but stiff porous dished member expansible and contractible under varying humidity conditions, and means for restricting outward expansion thereof.

3. In a hygroscopic device, a humidity-responsive controlling element comprising a thin mem-

ber expansible and contractible under varying humidity conditions and having a conical surface, means for restricting outward expansion at the base thereof, and means for applying thrust resulting from movement of the apex caused by 80 expansion and contraction thereof to move another member, comprising a combined adjusting and thrust transmitting screw threaded into and projecting from the apex, and a multiplying lever system actuated by said screw.

4. In a hygroscopic device, a controlling element comprising a relatively flat and rigid member having a relatively thin portion and a substantially frusto-conical surface, said member being expansible and contractible under varying humidity conditions, means for restricting outward expansion thereof at the base, and means for applying thrust generated by expansion thereof in another direction to actuate desired apparatus, comprising a multiplying lever system, and a combined thrust-transmitting and adjusting screw threaded into and projecting from the apex and connected to a portion of the lever system.
